CORD LOCK FOR VENETIAN BLINDS

Hans K. Lorentzen, Montclair, N. J., assignor to
 Lorentzen Hardware Mfg. Corp., New York,
 N. Y., a corporation of New York

Original application September 21, 1938, Serial
 No. 230,900. Divided and this application De-
 cember 31, 1940, Serial No. 372,461

4 Claims. (Cl. 24—132)

This invention relates to blind cord locks.

This application is a division of my copending application, S. N. 230,900, filed September 21, 1938, for Head-bar organization for Venetian blinds.

An object of the present invention is to provide a cord lock for Venetian blinds of such construction that a cord engaging dog is mounted to have the end of the dog press the cord against a part of a housing supporting the dog together with means for limiting the degree of movement of the dog into locking position.

Another object of the invention is to provide a cord lock so constructed that a dog associated with a pulley can move to press into locking engagement with cord below the pulley and also into braking relation to the cord and the pulley.

A further object of the invention is to provide a cord lock so constructed that a dog mounted in a housing has one end thereof engageable with vertical expanses of cord passing through the housing and has another part thereof engageable with expanses of cord passing around a pulley in the housing.

Other features, objects and advantages of the invention will be apparent by reference to the following detailed description of the accompanying drawing wherein

Fig. 1 is an end elevation of a cord locking device, such device being shown as being associated with a sheet metal head-bar construction, and

Fig. 2 is a section taken substantially on the line 2—2 of Fig. 1.

Referring now to the drawing 10 indicates generally a metallic head-bar organization which of itself forms no part of the present invention. Only a fragment of one end of the head-bar has been shown in the drawing.

The cord lock device constituting the present invention is made up of a sheet metal housing, indicated generally at 10', and comprising two side walls 12 and 14 connected in spaced relation by an intermediate wall 15, the walls being integral. This intermediate wall can either be straight or can be bowed outwardly as is customary in devices of this character. A plate 11 is secured in suitable fashion to edges of the side walls 12 and 14, and, in the illustration, is secured to parts of the head-bar for assembly purposes. The wall 15 extends from a point below the top of the walls 12 and 14 to the bottom termination of these walls, as is shown clearly in the drawing, and the actual bottom of the wall 15 can be flared outwardly a slight amount as 55

shown at 16. A pulley 17 is mounted for rotation between the side walls 12 and 14 with a part of the pulley extending outwardly beyond the wall 15 and the remaining part of the pulley 5 extending inwardly relative to this wall. A bar member 18 is mounted above the pulley to limit upward movement of cords 19 passing around the pulley.

A dog member indicated generally at 20 is pivotally mounted between the plates 12 and 14, such dog member being made up of two side walls 20' and an intermediate connecting wall 21. This connecting wall 21 has a terminal portion 22 bent at an angle to the main part of the wall. 15 The end of the terminal portion 22 can be straight or can be provided with teeth in the manner shown in my Patent No. 2,075,214.

The dog 20 is so positioned relative to the wall 15 and the pulley 17 that it can cooperate with 20 these parts and with the cords 19 to obtain a locking of the cord against movement in a manner more efficient than has been possible with prior art devices. By reference to Fig. 2, it will be noted that when the dog is moved into locking engagement cooperating with the parts, the end of the angular portion 22 of the dog presses the vertical expanses of the cord 19 against the wall 15. At the same time the upper surface of this angular part 22 presses against the cords 25 19 to bind them against the pulley 17. In this manner the dog acts not only to lock the cord against the wall 15 but also serves to simulate a brake pressing the cords against the pulley. The pulley, likewise in association with the cords, 30 19 to bind them against the pulley 17. In this manner the dog acts not only to lock the cord against the wall 15 but also serves to simulate a brake pressing the cords against the pulley. The pulley, likewise in association with the cords, 35 serves as a stop to limit clockwise rotation of the dog about its pivot. Thus the present arrangement provides a device in which the lift cords for a blind passing over a pulley and normally stressed to move upwardly, so far as vertical 40 expansive is concerned, are locked against such movement with a double action but at the same time the locking member is restrained against an extreme movement which might injure the cord, particularly if the end of the locking member is serrated or provided with teeth as is common practice. The pulley also 45 has the function of changing direction of movement of the lift cords so that they are readily accessible to an operator.

The device shown herein, while being illustrated as being mounted in an angular position relative to a metallic head-bar is capable of being used in connection with head-bars of other construction and materials. The device as shown is secured to the plate 11 by having

tongues thereof passing through openings in this plate and then staked thereto as shown at 30. Obviously the locking device can be associated at any desired angle and in any suitable relation to any type of head-bar, for which purpose it may be desirable to supply a closing wall member of different configuration to take the place of the plate 11.

From the foregoing it will be seen that the present invention provides an improved cord lock of double action versatility and accordingly it is to be understood that the device is not to be limited to the illustrated embodiment but only by the scope of the following claims.

What is claimed is:

1. In a Venetian blind a cord lock comprising a housing having as part thereof an abutment wall, a pulley rotatably mounted in said housing above said abutment wall, and a dog pivotally mounted in the housing, the end of said dog being movable to engage cord passing between the end of the dog and the abutment wall and around the pulley to press the cord firmly against said abutment wall, said dog having a length greater than the distance between the axis of movement of the dog and the periphery of the pulley effective to press the cord against the pulley when the cord is also pressed against the abutment wall.

2. In a Venetian blind a cord lock comprising a housing having as part thereof an abutment wall, a pulley rotatably mounted in said housing above said abutment wall, and a dog pivotally mounted in the housing, the end of said dog being movable to engage cord passing between the end of the dog and the abutment wall and around the pulley to press the cord firmly against said abutment wall, said dog having a portion of length greater than the distance between the axis of movement of the dog and

the periphery of the pulley effective to bind said cord between said portion of the dog and said pulley when the cord is pressed against the abutment wall by the end of the dog.

3. In a Venetian blind a cord lock comprising a housing having as part thereof an abutment wall, a pulley rotatably mounted in said housing above said abutment wall, and a dog pivotally mounted in the housing, the end of said dog being movable to engage cord passing between the end of the dog and the abutment wall and around the pulley to press the cord firmly against said abutment wall, said dog having a substantially flat portion adjacent the end to press the cord against the pulley at the same time the cord is pressed against the abutment wall by the end of the dog.

4. In a Venetian blind cord lock having a housing which the cords enter from one direction and leave in another direction, a pulley in the housing over which the cords pass to change direction, and a pivotal locking dog in the housing, the housing having an abutment wall, one end of the wall being adjacent to the pulley and the wall extending approximately in the direction of the cords leaving the housing; the improvement which comprises: the dog having a locking nose which moves toward said abutment wall and a locking portion which moves toward the pulley when the dog moves to locking position, the spacing between said nose and said wall in locking position being less than the cord thickness when the spacing between said locking portion and said pulley is approximately equal to the cord thickness, whereby the pulley limits the movement of said nose toward said wall and the cord is locked both against said wall and said pulley.

HANS K. LORENTZEN.
